UNITED STATES PATENT OFFICE.

CARL G. KOPPITZ, OF GREENSBURG, PENNSYLVANIA, ASSIGNOR TO RAILWAY AND INDUSTRIAL ENGINEERING COMPANY, OF GREENSBURG, PENNSYLVANIA, A CORPORATION OF PENNSYLVANIA.

OVERLOAD AIR-BREAK SWITCH.

1,316,901.

Specification of Letters Patent. Patented Sept. 23, 1919.

Application filed June 22, 1917. Serial No. 176,409.

To all whom it may concern:

Be it known that I, CARL G. KOPPITZ, a citizen of the United States of America, residing at Greensburg, in the county of 5 Westmoreland and State of Pennsylvania, have invented certain new and useful Improvements in Overload Air-Break Switch, of which the following is a specification.

This invention relates to air break switches such as are used on high tension circuits and, in particular, to that class of switches which are automatically opened when a heavy overload or short circuit occurs on the line.

10 While it is comparatively easy to provide satisfactory protection devices of this character for low potential circuits, the protection of high potential circuits presents more difficult problems to solve.

15 A certain degree of protection can, of course, be obtained by means of a horn gap fuse, but this fuse has the drawback, which can be sufficiently appreciated only in the practical operation of systems of this kind, 20 that the renewal is a tedious process and consumes considerable time.

Good protection may be afforded by the use of automatic oil switches, but the cost of such equipment is often prohibitive, especially in the case of small installations.

It is the object of the present invention to meet the above mentioned objections and produce a simple and effective device which is available for small and large installations alike.

In carrying out the object of my invention, I have introduced what I believe to be an entirely novel feature. I have mounted an automatic trip mechanism on the top of 40 an insulator which rotates to transmit power to operate directly or indirectly a main switch. By this arrangement it is possible to place the automatic trip on the "hot" side of a high tension power transmission system, instead of operating a grounded trip on the grounded side of the system. It is necessary to use an auxiliary trip which can be made of rugged construction to be in turn operated by the automatic trip which may 45 be of comparatively delicate construction.

50 While the features just pointed out are just as essential in connection with a single switch as with a multiple switch system, I illustrate the principles of my invention in

connection with, what I consider as a preferred embodiment, a multiple switch system.

In the drawings—

Figure 1 represents a multiple switch system, as applied to a three phase circuit in 60 elevation;

Fig. 2 the same system in side elevation; and

Fig. 3 is a plan view;

Fig. 4 shows a rotatable insulator and 65 automatic trip mechanism in vertical section;

Fig. 5 a plan view of the same, the protecting hood being shown in section;

Figs. 6, 7 and 8 are plan view, elevation 70 and end view, respectively, of the auxiliary trip mechanism, the protecting hood being removed;

Fig. 9 a plan view similar to Fig. 6, of 75 certain detail, parts of the structure being shown in section; and

Fig. 10 is a detail, partly in section.

In Figs. 1, 2 and 3, the switch system is shown as mounted on a support comprising a plurality of channel rails connected in 80 suitable manner to produce a strong and solid frame and facilitate the disposition of the various switch elements for co-operative relationship. Two pairs of channel beams 1, 1' and 2, 2' are interconnected by three pairs 85 of channel rails 3, 3', 4, 4', and 5, 5', through intermediate short lengths of rails so as to space slightly one set from the other for a purpose to be described later on.

Since these intermediate rails are all alike, 90 only one pair 6, 6' is indicated. Upon each of the rails 3, 3', 4, 4' and 5, 5' is mounted a set of insulators belonging to one line. Each set comprises an ordinary stationary 95 insulator, a rotatable insulator and two intermediate insulators mounted on a single rotatable base and forming the rotary part of each switch. Since the three switches are identical, the description of one applies to each.

The stationary insulator 7 carries at its top a line terminal 8, one half 9 of a horn gap switch and a clip 11. The rotary element comprises a base 12 pivoted to the support and carrying two insulators 13 and 14. 105 At the top the insulators support a knife blade 15 adapted to co-operate with the clip 11. A conductor 16 makes connection from

the rotatable insulator 10 to the knife blade 15 at a point vertically above the pivot of the base. To insure good electrical contact a flexible bonding wire 17 connects the conductor 16 and knife blade 15. That insulator on the rotary element which is opposite the stationary insulator 7, namely insulator 14 carries the other half 9' of the horn gap switch. The arrangement, which is substantially like that disclosed in the patent to Burke, 1,099,421, is such that the horns will still make contact when the blade 15 has left the clip 11 and will finally break the circuit. The rotatable insulator 10 supports at its top an automatic trip mechanism, normally covered by a hood 21.

Having special reference to Fig. 4, the insulator 10 comprises a pin 22 mounted for rotation in sleeve 23 which has a flange 24 for connection to a cross-rail. The sleeve 23 has an extension 23' below flange 24 to serve as a support and guide for a strong coil spring 25. This spring 25 has one end connected to a stationary part, as for instance the flange 24, and the other end to the sleeve 22' which is secured to the pin 22 by a key or bolt 122. The pin 22 has preferably, immediately above the sleeve 23, an overhanging shoulder 26 to prevent rain from getting into the bearing. The insulator, which is preferably of the petticoat type, has rigidly connected at the top a pin or shank 27 which carries at its upper end an arm 28 forming one element of the trip mechanism. Arm 28 is shown as attached to pin 27 by means of a sleeve 29 keyed to pin 27 by a screw 30.

The other elements of the trip mechanism are supported on a frame which is held stationary relative to the general supporting structure. This frame comprises a base 31 loosely surrounding pin 27 and resting on a shoulder 32 on the pin, an upright portion 33 and top portions 34 and 35. Top portion 34 has an aperture in alignment with the aperture on the base to receive the pin 27. Between the top portion 35 and an extension 36 on the base 31 is held trip coil 37. A stationary core 38 is supported in the plate 35 and extends a definite distance within the coil 37. A plunger or movable core 39 is confined within the lower part of the coil and carries a trip rod 40 extending upwardly through an aperture 41 in the stationary core. In order to adjust the position of the plunger so that it will be drawn into the coil at any desired overload current, I have provided an adjusting screw 42 having screw-threaded engagement with the plunger. The bottom of the screw terminates in a head 43 and a lock nut 44 is used to lock screw 42 in adjusted position. Between the nut 44 and the bottom face of the plunger I preferably place a guide plate 45 having lugs 46. A cylindrical casing 47

having a closed bottom incloses the lower portion of the plunger and the adjusting elements. This casing, which has slits 47 through which the lugs 46 on the guide plate 45 project, is secured to the lower face 70 of extension 36 as by screws 48. When the casing 47 is in place, the head 43 will rest on the bottom of the casing. On the outside of the casing I provide a scale to coöperate with lugs 46. The position of the lugs on 75 the scale indicates the distance of the head 43 from the bottom face of the plunger and therefore the position of the plunger in the coil. This is merely an ordinary way of adjusting overload relays. It is obvious 80 that the adjustment may be made in various other ways.

Current enters the terminal 49, passes through the primary of a current transformer 50 and then passes through the terminal board 51 to the line wire 52. The trip coil is connected across the terminals of the secondary of the current transformer 50, (not shown). It is understood that a current transformer may be dispensed with 90 and the trip coil may be connected in series with the line.

On the arm 28 is pivoted a latch 53 provided with a latch plate 54 made of special steel, such as tool steel. A spring 55 which is secured to the arm 28 at one end bears on latch 53 to press it downwardly to an extreme position determined by the engagement of shoulders on the latch and the arm 28 (not shown). This position is such that, 100 when the arm 28 is in operative position, the latch plate 54 will engage the upper edge of a stationary latch plate 56 secured to a shoulder 57 on the frame portion 35.

The various parts of the trip mechanism 105 and the insulator are so dispositioned that, when the latch 53 is locked against latch plate 56, the spring 25 is under tension. When an overload current rises to the predetermined strength, the plunger 39 is violently drawn into the coil and the trip rod 40 delivers a hammer blow against the latch 53 and thereby forces the latch upwardly so that it clears the latch plate 56. As the arm 28 is now free to swing, the insulator 115 will turn under the force of the spring 25. The turning movement is limited by shoulders (not shown) on the lower end of sleeve extension 23' and the sleeve 22'.

The part of my invention just described is 120 a most essential feature, since it transmits movement from an automatic trip located on the high-tension side of the transmission system through the high-tension insulator itself and thereby obviates the necessity of 125 an electrical connection from the high tension side to the switch operating mechanism and of special ground connections for protecting the operator.

In order to translate the movement trans- 130

mitted through the insulator for opening on the frame on the other side so that the circuit, which is of course the purpose of the trip mechanism, I have designed a special auxiliary trip 58 (see Figs. 1, 2 and 3). Each of the rotatable insulators has connected to the projecting end of pin 22 a forked crank 59 provided with a cotter pin 59' across the ends of the fork. Through the bifurcation of each crank passes a rod 60 having a thrust collar 61 adjacent each crank. When any one of the rotating insulators, under an overload as above described, turns under the force of its spring 25, the crank will deliver a hammer blow against the thrust collar 61 and thereby push the rod lengthwise. Where the rod 60 passes through the auxiliary trip mechanism 58 it is provided with a trip arm for operating the auxiliary trip.

Having special reference to Figs. 6 to 10, 62 shows the trip arm on rod 60. This arm is secured by any suitable means as by the set screws 63. The trip mechanism comprises a frame 64 having four apertured lugs 65 for securing it by means of screws or bolts to the supporting structure as to the channel beam 1. From the upper and lower portion of the back plate 66 project lugs 67 and 68. These lugs are apertured to receive an operating shaft 69 having a polygonal shank portion 70. Intermediate the lugs 67 and 68 are mounted a crank arm 71 and latch arm 72. The crank arm 71 is loosely mounted on shaft 69 while the latch arm 72 is secured to shaft 69 as by a screw 72'. Latch arm 72 has pivoted to its outer end 73 a latch 74 which has a free latching shoulder provided by a latch plate 75 made of special steel. The latch is actuated by a spring 74' to normally project toward crank-arm 71, its movement being limited by suitable shoulders 174 and 175 on the latch and latch arm. The crank arm 71 has a shoulder portion 76 against which the latch arm 72 bears in one direction, and a latch plate 77 of special steel against which latch plate 75 is adapted to bear in the opposite direction, if the latch is not otherwise prevented from doing so.

The latch arm 72 is provided with cam shoulders 78 straddling the rod 60 as the shaft 69 is rotated from right to left, as clearly seen in Figs. 6 and 7.

Shaft 60 is provided with a thrust collar 79 which for purposes of simplicity may be integral with the trip 62. When the latch arm is moved to the left by a movement of shaft 69 from right to left, the cam shoulders engage the collar 79 and move rod 60 to the right, as best seen in Fig. 9, and with it the trip arm 62. To prevent the rod 60 and trip arm 62 from turning, a shoulder 61' on the thrust collar 61 engages a shoulder plate 161 on the frame on the one side and a projection 62' contacts with a plate 162

in one plane. Normally, when the trip mechanism is in operative position *i.e.*, when the switches are closed, rod 60 is in its extreme position to the right and held thereby by the latches 53, (Fig. 4) as above explained. Crank arm 71 and latch arm 72 are also in their extreme position to the right, having been brought into that position by a turning of the shaft 69 to the right as previously described, whereby through connecting bar 80 and crank 81 (see Fig. 2) the rotating element 12 of one of the switches, preferably of the center switch as shown, is closed 88 against the tension of a strong spring 82. When now the trip coil 37 of one of the rotating switches operates its plunger to release latch 53 and the insulator is free to swing due to the force of spring 25, rod 25 60 will be pushed with great force to the left and deliver a violent blow by means of the trip arm 62 against the latch 74, thereby releasing crank arm 71 which under the force of spring 82 will swing to the left to 90 its extreme position in that direction. The spring 82 at the same time turns the rotating element of the switch and opens the circuit.

In order to reset the switches it is merely necessary to turn shaft 69 to the left, thereby 95 forcing rod 60, as previously described, to the right and freeing the latch of contact with the trip arm 62 and at the same time resetting the primary trip mechanism against the tension of spring 25, then, when 100 the latch plate 75 has engaged latch plate 77 on the crank arm 71, to turn the crank arm 71 against the tension of the spring 82 to the right by a right hand movement of the shaft 69 and to lock the shaft 69 in that 105 position to hold the switches closed. To conveniently operate shaft 69, a rod 83 having a socket 84 to fit the polygonal shank portion 70 is connected to the shaft 69. At the lower end of rod 83 is pivotally attached 110 a locking handle 85 which may be locked in its extreme positions by swinging it down into engagement with suitable clips on plate 85' or in any other desired way.

A special feature of the auxiliary trip 115 mechanism 58 is the form of the trip arm 62. This trip arm is cut substantially concentrically with the shaft 69 and of such length that it will be in a position to trip the latch 74 on latch 72 during the greater 120 part of the angular movement of the latter from its extreme left position to its extreme right position. The purpose of this arrangement is to safeguard the switch system and the line, if a heavy overload or short 125 circuit should exist at the time of closing the switches. The arrangement is such, that the trip is operated as soon as the horns come in contact *i.e.*, some time elements in advance of the closing of the switches them- 130

6 selves. Under the assumed conditions, as soon as the horns touch, the overload current will operate the main trip and rod 60 will receive an impulse to the left and trip arm 62 will strike the latch 74 before the right hand movement of the latch has proceeded very far so that the spring 82 returns the rotatable element of the switches to their open position, before they are closed.

10 The rotatable elements 12 of the three switches are interconnected by rods 87 and 88 so that upon the action of one of the main trips all three switches are simultaneously opened.

15 While I have described a specific construction embodying my invention in order to facilitate a full understanding of the principles governing it, it is obvious that my invention can be applied in various other 20 ways, to other systems and may be carried out in different forms. The details I have shown are merely referred to for purposes of illustration and do not in any sense constitute limitations.

25 I claim:

1. In an electric circuit the combination of a rotatable insulator, an automatic trip located at the line side of the insulator and means for transmitting the action of the 30 trip through the insulator.

2. In an electric circuit the combination of a rotatable insulator, an automatic relay, means for locking the insulator in one position when the relay is inoperative and 35 means tending to turn the insulator to another position.

3. In a high tension circuit the combination of a stationary support, an insulator rotatably mounted in said support, an automatic trip mounted on the top of the insulator and means for transmitting the action of the trip through the insulator.

4. In a high tension circuit the combination of a stationary support, an insulator 45 rotatably mounted in said support, an automatic trip mounted on the top of the insulator, locking mechanism between the insulator and the trip and means for rotating the insulator when said lock is broken.

5. In a high tension circuit the combination of a trip mechanism energized by the said circuit, a support and an insulator rotatably mounted thereon, means for interlocking the insulator and the trip mechanism, means for rotating the insulator when the lock is broken and means for bringing the insulator back to interlocking position.

6. In a high tension circuit the combina-

tion of a trip mechanism energized by the said circuit, a support and an insulator 60 rotatably mounted on said support, a pin extending from the insulator carrying a latch arm and a latch for locking the insulator in suitable position relatively to the trip mechanism, and means for rotating the insulator 65 when the latch is disengaged by the trip mechanism.

7. In a high tension circuit the combination of a main trip mechanism, a rotatable insulator, an auxiliary trip mechanism 70 and means for transmitting the action of the main trip through the insulator to the auxiliary trip mechanism, said means comprising a rod connected at one end to the rotatable insulator and connected at its 75 other end to the auxiliary trip mechanism through a tripping arm.

8. In a high tension circuit comprising a plurality of lines, the combination of a plurality of automatic trip mechanisms, each 80 responsive to one line, a rotatable element of insulating material associated with each of said trip mechanisms and having one end connected thereto, an auxiliary trip mechanism, and a connecting rod connected to 85 the other end of each of said rotatable elements and to the auxiliary trip mechanism.

9. A trip mechanism comprising a support, a shaft mounted thereon, an arm loosely turning on the shaft, an arm secured to the shaft, a latch carried by the second arm and adapted to engage the first arm to lock the two arms against relative movement in one direction, a rod mounted for reciprocating movement, a cam on the 95 rod adapted to strike the latch to disengage it from the first arm when the rod is moved in one direction, and means on the shaft and the rod for moving the rod in the opposite direction.

10. A trip mechanism comprising a support, a shaft mounted thereon, an arm loosely turning on the shaft, an arm secured to the shaft, a latch carried by the second arm and adapted to engage the first 105 arm when the shaft is rotated in one direction, a rod mounted for reciprocating movement, a cam on the rod adapted to strike the latch to disengage it from the first arm when the rod is moved in one direction and 110 a cam on the shaft and a shoulder on the rod for moving the rod in opposite direction when the shaft is rotated in the opposite direction.

In testimony whereof, I affix my signature. 115
CARL G. KÖPPITZ.
